CLAIM

The ornamental design for a crop harvester attachment for combines and grain harvesters, as shown and described.

DESCRIPTION

FIG. 1 is a perspective view of a crop harvester attachment for combines and grain harvesters, showing my new design, the manifold being plain and unornamented;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is an enlarged fragmentary perspective view of the nozzle, the other nozzles being identical.

FIG. 2.

FIG. 7

FIG. 5.

FIG. 4.
